FREDERICK SHICKLE, OF ST. LOUIS, MISSOURI, ASSIGNOR TO SHICKLE, HARRISON, AND COMPANY, OF SAME PLACE.

Letters Patent No. 90,591, dated May 25, 1869.

IMPROVEMENT IN APPARATUS FOR MOULDING PIPE.

The Schedule referred to in these Letters Patent and making part of the same.

To all whom it may concern:

Be it known that I, FREDERICK SHICKLE, of St. Louis, in the county of St. Louis, and State of Missouri, have made certain new and useful Improvements in Devices for Moulding Pipe, and for similar purposes; and I do hereby declare the following to be a full and true description thereof, reference being had to the accompanying drawings, and to the letters of reference marked thereon.

For the purpose of forming an improved mould for casting pipes, columns, and similar cylindrical bodies, the nature of this invention is in supporting the pattern-frame and flasks, or moulds in a vertical position, upon hinges, in such wise that the relative position of the parts shall be determined by said hinged adjustment, to insure accuracy of joint and fit in the finished mould; secondly, to permit the operator to properly ram the sand about projecting flanges, or bell-ends.

The nature hereof is in the arrangement of the flask, or pattern, with exterior openings, to allow the introduction of rammers.

To enable those herein skilled to make and use my said improved device in moulding pipe, or similar bodies, I will now more fully describe the same, and the application thereof, referring to

Figure 1 as a plan view, with certain parts removed to develop others underlying; to

Figure 2 as an elevational front view; to

Figure 3 as a horizontal sectional elevation at (the bell-end of the frame, say) the line *x y* of fig. 2; to

Figure 4 as a vertical sectional elevation of the hinged support for the flask and frame.

I arrange a pit, in which the moulds are operated. Said pit is surrounded by the wall *A*, to which are secured, by a strong cast-iron frame, the pivot-bearings *B*, having a proper rest, *B'*, upon which the weight of the moulding-devices is taken.

Connecting with the pivots *B*, and resting upon the shoulders *B'*, I arrange the exterior case, or flask *C C'*, divided into equal parts, *C* and *C'*, each connected by separate loops, *c* and *c'*, respectively, to and with the pivots *B*.

When the flask *C C'* is thus hung, and rests with its parts opened wide, then the inner pattern-frame *D* is connected, by its hinges *d*, with the pivot *B*.

In the frame *D* are arranged the patterns *E*, conforming, by their outer surface, accurately to the interior of the casting to be produced, and the juxtaposition of the parts *C C'* and *E* is then to be such, that when the parts are properly in contact, the semi-annular space between the pattern and flask shall be sufficient to admit the proper quantity of moulding-sand.

For this purpose, the flask *C C'* will be swung to meet the radial ribs *F F'*, the joint being made a close fit, and secured by proper clamps *f*.

The gate, or runner *G* will be left at the ribs *F F'*, and as said ribs accurately terminate the semi-cylindrical

space of each half flask *C C'*, when the sand is rammed in the mould thus formed, it will form edges along the ribs *F F'*, which, when the half flasks are joined, will actually fit to complete the cylinder of the mould, as required.

In order to preserve the edges of the sand at the ribs *F F'*, I have arranged to withdraw the patterns *E* from the sand, and for this purpose the shaft *H* is secured in proper bearings in the frame *D*.

Upon said shaft are the cams *h*, operating (by suitable straps) the cam-rod *I*, which attach directly to the patterns *E*.

By turning the shaft *H* by a hand-crank, (or other means,) the patterns *E* are receded, and thus leave the sand in the half flasks, a true impression of the outer surface of the pattern *E*.

As it is advantageous to cast gas and water-pipe with the swelled "bell-ends" down, I arrange the flask *C* in such wise, that the operator may ram the end from without.

For this purpose, the flask *C C'* has, at its base, the openings *c*, in such position, that the operator may introduce and ram the sand about the projecting end of the pattern *E*.

A proper cover, *c'*, is then placed to close the openings *c*, and held down by keys *c'*, or any other suitable devices.

The exterior mould being completed, and the pattern *E* having been receded by the operation of the shaft *H*, the clamps *f* are released, and the flasks *C C'* are swung back, to disengage from the patterns *E*. The pattern-frame *D* is then lifted off the pivot *B*, by suitable derrick, or lifting-devices, and may be at once used in a second flask, in the manner hereinbefore described.

The moulds in the flasks are then blackened or painted, and the flask *C C'* is closed, and, being clamped, may be lifted off the bearings *B*, to be dried, as in the usual processes, preparatory to being used for casting.

Having thus fully described my said invention,

What I claim, is—

1. Supporting the flasks *C C'* and pattern-frame *D* vertically, by hinges, upon bearings *B B'*, substantially as set forth.

2. The half flasks *C* and *C'*, and their terminal ribs *F F'*, combined with the movable patterns *E*, and the devices for moving the same into and from contact, substantially as and for the purposes set forth.

3. The flask *C C'*, arranged with openings *c*, for ramming the sand about bell-ends, and similar projections, substantially as set forth.

In witness of said invention, I have hereunto set my hand, in the presence of—

FREDERICK SHICKLE.
